MOTHPROOFING COMPOSITION

Henry Martin and Rudolf Hirt, Basel, Switzerland, assignors to the firm J. R. Geigy S. A., Basel, Switzerland

No Drawing. Application May 1, 1937, Serial No. 140,265. In Switzerland May 9, 1936

6 Claims. (Cl. 167—37)

According to the present invention, textiles and other materials liable to damage from moths are rendered moth-proof by treating them with mixtures or solutions of thianthrene and its derivatives and substitution products. These agents are used in the manner customary for insecticides.

Many compounds of the thianthrene series suitable for use in the invention are known. The following are some of them; they are given by way of example and the invention is not limited to their use:

Thianthrene or 2:6-dimethylthianthrene (Berichte, Vol. 29, pages 437—8); 1:3:5:7-tetra-methylthianthrene (Berichte, Vol. 22, page 910); 2-chlorothianthrene or 2:7-dichlorothianthrene (Annalen der Chemie, Vol. 381, pages 327 and 329); 2:7-dichloro-3:6-dimethyl-thianthrene, thianthrenedicarboxylic acid or dimethoxythianthrene (Chem. Zentralblatt, 1922, Vol. I, page 818); 2:3:6:7-tetramethoxythianthrene (Annalen der Chemie, Vol. 468, pages 162—201, Chem. Zentralblatt, 1929, Vol. I, page 1944); dinitrothianthrene (Bull. de la Soc. Chimique de Paris, Ser. 3, Vol. 15, page 423); 3-nitro-6-methylthianthrene, 3-nitro-8-methoxy-5-methylthianthrene, 6-chloro-3-nitrothianthrene, 5:8-dichloro-3-nitrothianthrene or 3-amino-6-methylthianthrene hydrochloride (Chem. Zentralblatt, 1924, Vol. I, pages 1035—6); thianthrenesulphonic acid (U. S. Specification No. 1,589,390 and Chem. Zentralblatt, 1927, Vol. I, page 360); naphthianthrene (Berichte, Vol. 42, page 1175) and so on, also the S-oxides of the above compounds, for example:

Thianthrene-S-oxide (Annalen der Chemie, Vol. 381, page 321); thianthrene-S-dioxide (Berichte, Vol. 44, page 758); thianthrene-monosulphone (Annalen der Chemie, Vol. 381, page 323); thianthrene-di-sulphone (Berichte, Vol. 29, page 442); 2:6-dimethylthianthrene-S-oxides (Berichte, Vol. 42, page 1174); 2:3:6:7-tetramethoxythianthrene-S-oxides (Annalen der Chemie, Vol. 468, pages 162—201, and Chem. Zentralblatt, 1929, Vol. I, page 1944) and so on, or thianthrene-S-disulphides, for example 3:7-dimethoxy-2:6-dioxythianthrene disulphide (Chem. Zentralblatt, Vol. II, page 898) and the like.

The aforesaid thianthrenes are excellently suit-

ed, for example, for protecting wool, hair, fur, feathers and the like by impregnation from damage by moths. Even when used in very small concentrations they impart a sufficient protection to the treated materials. In practice they will be used principally in the form of solutions in water or cheap organic solvents such as hydrocarbons, chlorinated hydrocarbons, alcohols, ketones or the like, or mixtures thereof. The goods to be protected may be treated by brushing or spraying or impregnated by immersion. Furthermore, the thianthrenes may be emulsified in oils, fats or creams, or they may be used as additions to powders and, indeed, in all the forms usual for insecticides. They may likewise be used in combination with other agents already known for the same purpose.

The following example illustrates the invention, the parts being by weight:—

20 parts of thianthrene or another of the compounds above-named, such as dimethylthianthrene, dichlorodimethylthianthrene or thianthrene-S-oxide, are dissolved in 980 parts of alcohol. Furs, feathers or wool are immersed in the solution and then centrifuged and dried. The goods thus treated are immune from damage by moths. Even more dilute solutions suffice to impart a satisfactory protection.

What we claim is:—

1. A moth-proofing composition containing as its essential active ingredient a thianthrene.
2. A moth-proofing composition containing as its essential active ingredient a thianthrene-S-oxide.
3. A moth-proofing composition containing as its essential active ingredient a thianthrene substituted by at least one halogen atom.
4. A moth-proofing composition containing as its essential active ingredient thianthrene-S-oxide.
5. A moth-proofing composition containing as its essential active ingredient dichloro-thianthrene-S-oxide.
6. A moth-proofing composition containing as its essential active ingredient dichloro-thianthrene.

HENRY MARTIN.
RUDOLF HIRT.
